UNITED STATES PATENT OFFICE.

JOSEPH HUNTER DICKINSON, OF CRANFORD, NEW JERSEY, ASSIGNOR TO THE AEOLIAN COMPANY, A CORPORATION OF CONNECTICUT.

RECORD-REPEATING DEVICE FOR PHONOGRAHS.

1,300,135.

Specification of Letters Patent.

Patented Apr. 8, 1919.

Application filed June 19, 1916. Serial No. 104,424.

To all whom it may concern:

Be it known that I, JOSEPH HUNTER DICKINSON, a citizen of the United States, residing at Cranford, in the county of Union 5 and State of New Jersey, have invented certain new and useful Improvements in Record-Repeating Devices for Phonographs, of which the following is a specification.

10 My present invention relates to a record-repeating device for phonographs, the features and advantages of which will be apparent to those skilled in the art from an understanding of the following description 15 in connection with the drawings showing one of the specific embodiments my invention may take.

In the drawings, Figure 1 is a plan view of a phonograph embodying my invention, 20 only the rear end of the tone-arm being shown and the turn-table and motor-board being removed to show the underlying mechanism; Fig. 2 is an enlarged partial side elevation of said phonograph embodying my invention, the general view-point being that indicated by the arrow designated II in Fig. 1; Fig. 3 is an enlarged partial elevation from the view-point of the arrows III in Fig. 1; Fig. 4 is the same 25 from the view-point of the arrows IV; Fig. 5 is a diagrammatic view of the electrical circuit; Fig. 6 is an enlarged vertical section partly in elevation on the line VI—VI in Fig. 1; and Fig. 7 is the same on the line 30 VII—VII.

Describing now the devices of the drawings:—1 indicates the cabinet of the phonograph, 2 the motor-board or shelf, 3 the neck of the horn, 4 the laterally swinging 40 and vertically adjustable tone-arm operatively supporting the reproducer 5. 6 is the spring-motor having a shaft 7 carrying a large gear-wheel 8 driving the turn-table shaft 9 through the pinion 10 (Fig. 1), 11 45 being the record-supporting turn-table. The turn-table shaft 9 has the usual gear connection 25 (Fig. 4) with the governor 26. 12 is an arm extending downwardly from the tone-arm through a slot in the motor-board and thence horizontally. Its free-end horizontally supports a flat strip 14. The motor-frame has a pair of depending arms 15 (Figs. 3, 2 and 1) which support an inverted U-shaped frame 16 pivoted 50 thereto at 17. Rigid with this frame 16 is

a cross-wise sleeve 18 wherein is an axle 19 having a large friction-wheel 20 at one end adapted to bear upon and be driven by the gear-wheel 8 of the motor to drive said axle 19 and a small friction-wheel 21 on its other end. 22 (Figs. 1 and 2) is an arm on the cross-bar of the U-shaped frame suitably connected with the core of an electro-magnet 23 by which the frame may be tilted into the position shown in Figs. 1, 2 and 3 about its pivots 17 so that its friction-wheels 20 and 21 are brought into contact respectively with the face of the motor-wheel 8 and the underside of the strip 14. The result is two-fold—first the strip 14, arm 12 and tone-arm are lifted to take the sound-box off the record, secondly a driving connection is made between the motor and the strip 14 whereby the latter is caused to travel endwise like a moving platform and to carry with it the tone-arm and reproducer which are thereby returned to a beginning point on the record for a repetition thereof. 24 is a tension spring having an opposite action on the arm 22 of the tilting frame from the electro-magnet 23, so that when the latter is de-energized, said spring tilts said frame to release the driving connection afforded thereby between the motor and the strip or movable platform 14, so that the latter together with the reproducer ceases to be driven in return direction across the record, and furthermore is at the same time lowered on to the record to begin a further playing or repetition thereof.

27 designates a pair of normally open electrical contacts supported by the block 28 of insulating material on a sub-shelf or board 29 (Figs. 1 and 2) under the motor-board; and 30 designates a pair of similarly supported but normally closed contacts and on the opposite or return side of the tone-arm. The contacts are electrically connected with magnet 23 as in Fig. 5 but before describing this, I will first describe the means by which each pair of contacts is adapted to be operated by the arm 12 (Figs. 1 and 2) after the tone-arm and reproducer have traveled any chosen distance across the record in either playing or return direction. 105 These devices are duplicated in connection with each pair of contacts 27 and 30, so that a description of one set will suffice for both, as follows:—31 (compare Figs. 1, 2, 6 and 7) is a plate secured across a slot 32 in the 110

sub-shelf 29. 33 is a part pivoted at one end 34 to the plate 31 and connected at its other end through intermediate insulation 35 with the movable contact of the given pair of contacts, so that the movement of the said part 33 will act to shift said movable contact due to its connection therewith. 36 is a pin projecting up through an enlarged hole in the plate 31 to provide plenty of clearance and 10 thence with reciprocating fit through a hole in the part 33. This pin 36 has a vertically elongated eye 37 through it, best shown in Fig. 7, through which is inserted a long rod 38 having an up-turned end 39 adapted 15 to be struck by the arm 12 on the tone-arm to operate the given set of contacts 27 or 30. This rod 38 is frictionally gripped between the top of said eye 37 and the face of the part 33 due to the downward pressure of a 20 leaf-spring 40 secured to the part 33 and pressing downwardly on top of the pin 36, and by reason of that fact, the movement of said rod will cause a swinging movement of the said pivoted part 33 in the same direction, the pivoted part shifting the movable contact 27 or 30, as explained above. Next 25 manual or finger means is provided for temporarily releasing said grip of the pin 36 on the rod 38 comprising a tilting lever 41 located in the slot 32 (compare Fig. 6) and pivotally supported by a projection 42 from the plate 31, one end of said lever underlying the pin 36 and its other end being pivotally connected with the stem 43 extending up 30 through a hole in the motor-board (cf. Fig. 2) and provided above said board with a head or button 44. Finally referring again to the long rod 38, this is guided not only by the referred-to eye in the pin 36 but also at its other end by a hole in a fixed bearing member 45 (cf. Fig. 1). Further a compression spring 46 surrounds the rod between said fixed bearing member and a collar 47 thereon, whereby the rod is given a 35 tendency to slide endwise against the arm 12. By the devices just described, the up-turned ends 39 of the respective rods 38 (cf. Figs. 1 and 2) can be located at the chosen points between which the record is to play and automatically repeat itself as will appear later from the description of the complete mode of operation of the invention.

The aforesaid pairs of contacts 27 and 30 are connected in circuit with a source of electricity 48 (Fig. 5), with said electromagnet 23 and with a third pair of normally open contacts 49 which are closed by the magnetic attraction of said electro-magnet whenever it is energized, all as shown by the circuits in said Fig. 5. Fig. 1 shows how the springs 46 on the rods 38 exert their tension on said rods in a direction to keep the contacts 27 normally open and the contacts 30 normally closed.

Describing now the mode of operation as

a whole:—The record and turn-table being at rest, the reproducer is placed on the record in the chosen groove for the ending of the playing; and the upper button 44 in Fig. 1 is pressed down which results (cf. Figs. 70 2, 6 and 7) in lifting the pin 36 in the part 33, thereby releasing the grip on the rod 38, which is thereupon impelled toward the arm 12 by its spring 46 until its up-turned end 39 (cf. Figs. 2 and 1) strikes against said 75 arm. The button is then released which automatically restores the grip or locking connection between the rod and the part 33. In short, the rod 38 for operating the contacts 27 has been set so as to end the playing of 80 the record and inaugurate the return of the reproducer at the chosen point.

The operator next lifts up the reproducer, returns it across the record and lowers it thereon in the groove chosen for the repetition of the record to begin; and then presses the lower button 44 in Fig. 1 which results as before in its rod 38 automatically adjusting itself into a position wherein its up-turned end is abutting against the arm 12 90 of the tone-arm.

The operator then starts the motor and the record is rotated and plays as usually, until the reproducer in feeding across the record reaches the chosen ending-place, 95 whereupon the arm 12 strikes against the up-turned end 39 of the upper rod 38 in Fig. 1, forcing it slightly endwise sufficiently to close momentarily the contacts 27 (Fig. 1), whereupon (compare Fig. 5) the battery circuit will be closed through the magnet 23 by way of the wires 50 and 51, which causes said magnet to attract its armature 53 to close the contacts 49, whereupon the current now continues to energize said magnet indefinitely by way of contacts 30, wire 52, contacts 49 and back again to the source through wire 51. In short, the described momentary closing of the contacts 27 has resulted in the continued energizing of the 100 magnet 23, which thereupon tilts the frame 16 so as to make the friction-wheel driving-connection between the motor-wheel 8 and the movable-platform member or strip 14, which latter is thereby lifted to lift the reproducer off the record and is then driven in the direction of returning the reproducer to the starting point on the record. At this point, the arm 12 strikes against the up-turned end 39 of the lower rod 38 in Fig. 1 105 and thereby opens the contacts 30, which instantly breaks the aforesaid circuit which has been keeping the magnet 23 energized, which thereupon drops its armature 53 (cf. Fig. 5) and releases its core 55, so that the 110 spring 24 (cf. Fig. 2) then acts to tilt the frame 16 back into the position wherein its rotary part no longer forms a driving connection between the motor wheel 8 and the part 14, which same act simultaneously per- 115

mits the part 14 to lower until the reproducer needle again contacts with the rotating record at the chosen place for the repetition to begin. Thus the record automatically replays itself between any two chosen points and will keep this up indefinitely until the motor is stopped.

5 My invention combines effectiveness with an advantageous simplicity; and further 10 combines other advantages such as that its devices are adapted to be concealed beneath the top-shelf or deck of the instrument showing only the two operating buttons 44 on either side of the tone-arm.

15 The electro-magnet is adapted to act as its own dash-pot by making its core 55 slide snugly in a cylinder 54 closed at the bottom and fixed in the center of the magnet. 56 is a bleed-hole in the wall of the cylinder. 20 Thus when the current is cut off from the magnet by the opening of the contacts 30 as described, the dash-pot action on the core controls the release of the reproducer to the record so that it settles down slowly preventing any injury thereto.

What I claim is:

1. In a record-repeating device for phonographs, the combination of a motor, a reproducer supported for adjustment to and 30 from playing position and for travel in playing direction across the record and return, and a releasable driving connection between said motor and the reproducer which when made, returns the reproducer across the record, said connection comprising an elongated member connected with the reproducer support and a rotary part adapted to be driven by the motor and to directly contact with and shift said elongated member end- 40 wise.

2. In a record-repeating device for phonographs, the combination of a motor, a reproducer supported for adjustment to and from playing position and for travel in playing 45 direction across the record and return, a releasable driving connection between said motor and the reproducer which when made, returns the reproducer across the record, said connection comprising an elongated 50 member connected with said reproducer support and a rotary part adapted to be driven by the motor and to directly contact with and shift said elongated member, and means set into operation by a given travel of the 55 reproducer in playing direction which moves the reproducer off the record and makes said driving connection.

3. In a record-repeating device for phonographs, the combination of a motor, a reproducer supported for adjustment to and 60 from playing position and for travel in playing direction across the record and return, and a releasable driving connection between said motor and the reproducer which when

made, returns the reproducer across the record, said connection comprising a platform connected with the reproducer support and a rotary part adapted to make frictional contact at one end with the face of a rotary part of the motor and at the other end with 70 said platform.

4. In a record-repeating device for phonographs, the combination of a motor, a reproducer supported for adjustment to and from playing position and for travel in 75 playing direction across the record and return, a platform rigidly connected with the reproducer support, and a rotary part driven by the motor and adjustable against said platform to take the reproducer out of contact with and return it across the record.

5. In a record-repeating device for phonographs, the combination of a motor, a reproducer supported for adjustment to and from playing position and for travel in 85 playing direction across the record and return, a platform rigidly connected with the reproducer support, a rotary part driven by the motor and adjustable against said platform to take the reproducer out of contact 90 with and return it across the record, and means set into operation by a given travel of the reproducer in playing direction for adjusting the rotary part as aforesaid against the platform.

6. In a record-repeating device for phonographs, the combination of a motor, a reproducer supported for adjustment to and from playing position and for travel in playing direction across the record and return, a platform rigidly connected with the reproducer support, a rotary part driven by the motor and adjustable against said platform to take the reproducer out of contact with and return it across the record, means 105 set into operation by a given travel of the reproducer in playing direction for adjusting the rotary part as aforesaid against the platform, and means set into operation by a given travel of the reproducer on its return 110 which releases the rotary part from driving the platform and releases the reproducer to the record.

7. In a record-repeating device for phonographs, the combination of a motor, a reproducer supported for adjustment to and from playing position and for travel in playing direction across the record and return, a releasable driving connection between said motor and the reproducer which when made, returns the reproducer across the record, said connection comprising a platform connected with the reproducer support and a rotary part adapted to be driven by the motor and to directly contact with and drive 120 said platform, means set into operation by a given travel of the reproducer in playing direction which moves the reproducer 125

- off the record and makes said driving connection, and means set into operation by a given travel of the reproducer on its return which releases said driving connection and 5 releases the reproducer to the record.
8. In a record-repeating device for phonographs, the combination of a motor, a reproducer supported for adjustment to and from playing position and for travel in 10 playing direction across the record and return, a releasable driving connection between the motor and the reproducer support which connection, when made, returns the reproducer across the record, an electro-magnet 15 for moving the reproducer off the record and making said driving connection, means comprising a set of electrical contacts operated by a given travel of the reproducer in playing direction to energize said electro-magnet, means for maintaining said electro-magnet energized, and means comprising another set of electrical contacts operated by a given travel of the reproducer on its return to deenergize said electro-magnet to release 20 said driving connection and to release the reproducer to the record to play the same.
9. In a record-repeating device for phonographs, the combination of a motor, a reproducer supported for adjustment to and from playing position and for travel in 25 playing direction across the record and return, a releasable driving connection between the motor and the reproducer support which connection, when made, returns the reproducer across the record, an electro-magnet for moving the reproducer off the record and making said driving connection, means comprising a set of electrical contacts operated 30 by a given travel of the reproducer in playing direction to operate contacts to energize said electro-magnet, said last named means further comprising an endwise movable part tending to move against the travel of the reproducer, means which normally grips the endwise movable part and operatively relates it to said contacts, and manual means for momentarily releasing the grip on said part.
10. In a record-repeating device for a disk-record phonograph, the combination of a horizontal motor-board, a motor supported below the board, a turn-table operatively supported above the board, a vertically adjustable laterally swinging tone-arm and reproducer supported thereby, a horizontally disposed platform supported crosswise from the tone-arm below said board and rigidly connected to move with said tone-arm, and 55 a rotary part driven by the motor and movable against said platform in a direction to 60 raise it and thereby lift the reproducer off and return it across the record.
11. In a record-repeating device for a disk-record phonograph, the combination of a horizontal motor-board, a motor supported below the board, a turn-table operatively supported above the board, a vertically adjustable laterally swinging tone-arm and reproducer supported thereby, a horizontally disposed platform supported crosswise from the tone-arm below said board and rigidly connected to move with said tone-arm, a rotary part driven by the motor and movable against said platform in a direction to 65 raise it and thereby lift the reproducer off and return it across the record, contact means located below said board, a part carried by the tone-arm to set said contact means into operation after said tone arm has traveled a given distance in playing direction, means brought into action by the setting of said contact means into operation for moving the rotary part as aforesaid 70 against the platform, and a finger piece 75 above the board for adjusting the contact means so as to be actuated when the tone-arm has reached any given point in playing the record.
12. In a record repeating device for phonographs, the combination of a motor; a reproducer supported for adjustment to and from playing position and for travel in 80 playing direction across the record and return; a platform rigidly connected with the reproducer support; and a single part initially movable against said platform in a direction to raise it and thereby lift the reproducer out of contact with the record and subsequently operated by said motor to shift 85 said platform in a direction to return said reproducer across the record.
13. In a record repeating device for phonographs, the combination of a motor; a reproducer supported for adjustment to and from playing position and for travel in 90 playing direction across the record and return; a platform rigidly connected with the reproducer support; and a single part located beneath said platform movable upwardly against the latter to raise the same and thereby lift the reproducer out of contact with the record, said part and said platform having a subsequent relative longitudinal movement, so as to shift the platform in a direction to return a reproducer 95 across the record.

In testimony whereof, I have signed my name to this specification this 17th day of June, 1916.

JOSEPH HUNTER DICKINSON.

It is hereby certified that in Letters Patent No. 1,300,135, granted April 8, 1919, upon the application of Joseph Hunter Dickinson, of Cranford, New Jersey, for an improvement in "Record-Repeating Devices for Phonographs," an error appears in the printed specification requiring correction as follows: Page 4, line 41, claim 9, strike out the words "to operate contacts," and that the said Letters Patent should be read with this correction therein that the same may conform to the record of the case in the Patent Office.

Signed and sealed this 20th day of May A. D., 1919.

[SEAL.]

R. F. WHITEHEAD,

Acting Commissioner of Patents.
